United States Patent Office

Des. 175,253
Patented Aug. 2, 1955

175,253

HIBACHI

Morris Greenblat, San Francisco, Calif., assignor of one-half to Burn-Strauss, Inc.

Application May 3, 1954, Serial No. 30,298

Term of patent 14 years

(Cl. D81—10)

FIG. 1

FIG. 3

FIG. 2

FIG. 4

FIG. 5

Fig. 1 is a top plan view of a hibachi showing my new design;

Fig. 2 is a front elevation thereof;

Fig. 3 is an end elevation thereof;

Fig. 4 is a vertical cross section of the hibachi taken along the lines 4—4 in Fig. 1; and,

Fig. 5 is a horizontal cross section of the hibachi as taken along lines 5—5 of Fig. 2.

I claim:

The ornamental design for a hibachi, as shown.
